MANUAL BOOKKEEPING APPARATUS

John E. Rosso, Virginia, Minn.

Application August 24, 1938, Serial No. 226,483

3 Claims. (Cl. 282—29)

This invention relates to improvements in manual bookkeeping apparatus and has for its principal object the provision of means of simple construction wherewith a carbon copy of an entry made on any of various separate bookkeeping forms may be made simultaneously and accumulated on a proof sheet in convenient line arrangement therewith.

Another object of the invention is to provide 10 a backing board having holding and aligning means for loose leaf bookkeeping forms, including a pointer, and whereby the next available line of each form may be conveniently placed upon the board above similar lines on the other forms therebeneath, so that an entry made on the top form will be simultaneously recorded on all forms; carbon paper being placed between the forms for this purpose.

Another object of the invention is to provide 20 said holding and aligning means with a second pointer to indicate to the operator the last line on the top form which may be used without running off the page of some form therebeneath.

Other objects and advantages of the invention 25 will appear in the following description thereof.

Referring now to the accompanying drawing 30 illustrative of the present development of the invention in its preferred form, and wherein like reference characters indicate like parts:

Figure 1 is a plan view of my improved bookkeeping apparatus, with the clamping bar partly broken away.

Figure 2 is an enlarged end elevation of one 35 corner of said apparatus illustrating the relative position of the clamping bar.

In the drawing, the numeral 1 indicates a rectangular base or board of any material presenting a suitable smooth upper writing surface. 40 Adjacent the left marginal edge of said base are fixed a row of short upstanding pegs or pins 2, preferably of metal, and arranged in pairs, the pegs of each pair being spaced approximately one-quarter inch apart, and the pairs being spaced about an inch and one-quarter apart, 45 although it is obvious that the pegs may be spaced one-quarter inch apart continuously throughout the length of the board. For use with this board there may be provided any desired number or arrangement of multiple record forms 50 for the purpose of entering thereupon, with the aid of carbon paper therebetween, bookkeeping or other data, as hereinafter described. Adjacent the left hand edge of the forms they are perforated so that said perforations will register 55 with the pegs and thus the forms may be placed

on the board over the pegs in any relative position to each other.

In addition to the pegs, I have provided a hinged clamping bar 3 which is pivotally attached to the left of the row of pegs for the purpose of holding down and keeping the left hand margin of the record sheets from curling and becoming detached from the pegs. This clamping bar runs parallel to the row of pegs, and consists of a rectangular bar, preferably of metal, 10 and its hinged connection to the board comprises the pair of arms 4 at either end thereof, each arm being pivoted at its lower end to the board, as at 5, and at its upper end to the bar, as at 6, so that the bar with its attachments will always move parallel with the surface of the board, as clearly illustrated in Figure 2. A knob is indicated at 7 upon either end of the clamp bar for convenient manipulation thereof, from one position to another, and in Figure 2 it is shown 20 midway between the limit of its movement in either direction. When moved to the right to the limit of its movement the clamp rests upon the board immediately adjacent the row of pegs and overlapping the left hand margin of any 25 record sheets on the board and keeps said sheets from curling and becoming detached from the pegs. No spring tension is applied to the clamp inasmuch as its weight is sufficient to serve the purpose of keeping the record sheets engaged on 30 the pegs. When the board is ready to receive record sheets, the clamp is moved on its hinges to the left and away from the row of pegs, and after the sheets are properly placed it is moved to the right to hold them down and in engagement with the pegs.

A detachable line guide sheet, indicated at 8, is provided and which fits over the row of pegs in the same manner as the record sheets. This line guide assumes a position on the board substantially midway from top to bottom, leaving approximately one-third of the space at the top and one-third of the space at the bottom open for the obvious shifting of the record sheets thereover. The proof or journal sheet is placed 40 on top of the line guide, and then any other record sheets, such as a statement and a ledger sheet may be placed successively on top of the proof sheet, and the line guide covers only the area to be used for writing purposes, and is the 45 primary guide for the proof or journal sheet which stays in a fixed position until the entries are completed or it is filled to capacity, when it is replaced by another. This line guide is provided with heavy ruled horizontal lines num- 50 55

bered consecutively from top to bottom at the extreme left and right hand edges, and which numbers extend beyond the other sheets which may be superposed thereupon, so that the next 5 unused numbered lines on the record sheets may be placed on the pegs in their proper positions, using the proper line guide number from either the right or left hand side. The numbers on the line guide are conspicuously provided with printed indicators pointing to the respective lines and project to the right and left of the record forms so that they are visible at all times during and after the assembling of the record sheets. The heavy lines on the line guide serve the additional purpose of more readily locating entered 10 matter on the proof sheet, which is semi-transparent with no lines or printed matter whatever located thereon. Of course, it is obvious that this line guide may be printed directly upon the 15 surface of the backing board, and function equally as well.

To avoid the possibility of making entries on the top sheet when there is no further available 20 entry space on any one of the under sheets, I 25 have provided a stop indicator **9** which will automatically prevent further entries. This indicator is attached to the hinged clamp in such a manner that it is readily slideable from top to bottom in either direction to any desired position. In operation this indicator is moved to a 30 position one line below the last available line on any one of the record sheets as and when such sheets are engaged with the pegs. When the hinged clamp is moved to the right against the 35 row of pegs this indicator covers a portion of one entry line on the top sheet, thereby preventing any entry from being made on that particular line, and of course when the operator reaches that line for his next entry, he removes the 40 record sheet which is filled to capacity and replaces it with another.

To relieve any disturbance of the bottom proof or journal sheet, or the sheet of carbon paper covering it, and to facilitate the finding of the 45 correct starting line, I have provided an automatic starting indicator **10** which is slidably carried by the hinged clamp in the same manner as the stop indicator, and of course assumes a position on the clamp bar thereabove. This indicator **10** is arched as indicated at **11** so that it may be slid on the clamp over the pegs without engaging any of the same. It is also shaped so that when the two indicators come together, it will slide over and cover the stop indicator. 50 In operation, this indicator is naturally positioned to point to the starting line on each sheet so that the next available line on each record sheet may be placed directly over one another when assembled on the board, so that, with carbon 55 paper between the sheets, an entry on the top sheet will be duplicated on the next available line for entry on each of the sheets successively therebeneath. If several entries are to be made on one sheet, this indicator must be moved down 60 one space before each of the entries may be made, and it is obvious from this procedure that 65 the start indicator is always covering the next

available writing line, and, when the hinged clamp bar is moved to the left, it is pointing to the proper line for the next set of record sheets.

No specific record sheets are illustrated in the drawing, as, from the above description, any of several different types comprising a particular bookkeeping system may be used with carbon paper therebetween to record the same entry simultaneously on all record sheets used in co-operation with the board. 10

The indicators **9** and **10** are formed integrally with their respective slideable members **12** and **13**, which latter are illustrated as being conveniently manipulated by the upstanding handles **14**. 15

Having thus described my invention, what I claim and desire to secure by Letters Patent, is:

1. Manual bookkeeping apparatus comprising in combination a backing board to receive a plurality of separate loose-leaf ruled bookkeeping forms perforated along one edge, a row of pegs carried by said board to receive the perforated side of said forms and hold same in predetermined relationship to other forms on the board, a movable clamping bar attached to said board and engageable with said forms upon one side of said pegs, and an indicator slidably supported by said clamp for designating on the other side of said pegs a line on any or all of said forms, said indicator being arched to extend over said pegs so that it may be moved without contacting said pegs. 20

2. Manual bookkeeping apparatus comprising in combination a backing board to receive a plurality of separate loose-leaf ruled bookkeeping forms perforated along one edge, a row of pegs carried by said board and spaced to correspond to said perforations to receive the perforated side of said forms and hold same in predetermined relationship to other forms on the board, a clamping bar attached to said board and movable to one position for holding said forms upon said pegs and to another position free of and to permit convenient adjustment of said forms upon said board, and an arched indicator slidably supported by said clamp and extendable over said pegs when said clamp is in one position for designating a line on any or all of said forms. 35

3. Manual bookkeeping apparatus comprising in combination a backing board to receive a plurality of separate loose-leaf ruled bookkeeping forms perforated along one edge, a row of pegs carried by said board adjacent one edge thereof to receive the perforated edge of said forms and hold same in predetermined relationship to other forms on the board, a movable clamp bar hingedly attached to opposite ends of said board adjacent said pegs and engageable with said forms upon one side of said pegs and movable free of said board for convenient manipulation of the forms upon the pegs, and an arched indicator slidably supported by said clamp for designating on the other side of said pegs a line on any or all of said forms. 50
